UNITED STATES PATENT OFFICE

KNUT LARSSON, OF STOCKHOLM, SWEDEN, ASSIGNOR TO TELEFONAKTIEBOLAGET L. M.
ERICSSON, OF STOCKHOLM, SWEDEN, A COMPANY OF SWEDEN

TELEPHONE SYSTEM

Application filed June 9, 1930, Serial No. 460,017, and in Sweden June 21, 1929.

In telephone plants of the central battery LR at the contacts 1, 2, 3, 4. The line relay LR is deenergized and opens the circuit of the relay SR. The cut-off relay BR remains thereupon energized over the contacts 5, 6 whereas the call meter now is disconnected 55 at the contacts 6, 7. Call metering may also be brought about in known manner by connecting the wire c to the negative pole of the battery, the cut-off relay BR being short-circuited. When 60 the relay BR for this reason is deenergized the call meter SM is connected into circuit to the test wire over the contacts 6, 7 the call meter being then actuated.

The present invention has for its object to reduce the cost of manufacture of the line and cut-off relays by a reduction in the number 15 of contact springs of said relay. This is brought about according to the invention by that those contact springs of the cut-off relay, which control the circuit extending over the test wire, are adapted to be actuated by the 20 line relay when the latter is energized.

The invention will be more closely explained with reference to the accompanying drawings, on which Figure 1 shows a known arrangement of the line and cut-off relays 25 and the appertaining circuits whereas Figure 2 shows a corresponding arrangement according to the invention. Figure 3 discloses an example of the constructional features.

Figure 1 shows a subscriber's line of which the two branches a, b together with the appertaining test wire c are connected to fixed contacts ak, bk, ck in the contact field of a call finder. To the subscriber's line belongs 30 the line relay LR, a cut-off relay BR and a call meter SM.

Upon a call, the line relay LR is energized in known manner over the subscriber's line, a call finder being started through the 35 medium of the starting relay SR the circuit of which is closed over the contacts 8, 9 of the line relay. At the same time the cut-off relay BR is connected to the test wire c over contacts 10, 11 of the line relay besides which 40 the call meter SM is disconnected from the test wire c at the contacts 12, 13. When the call finder finds the calling line a circuit is closed over the test wire c and the contacts 45 10, 11 through the cut-off relay BR which 50 is energized and disconnects the line relay

The circuit arrangement shown in Figure 65 1 may according to the invention be simplified in a manner shown in Figure 2. The group of contact springs 5, 6, 7 is here so disposed that it may be actuated by both the 70 cut-off relay BR and the line relay LR. Here- 75 by the contact spring group 10, 11, 12, 13 marked in Figure 1 by a dashed and dotted circle becomes superfluous at the same time as the circuits are simplified. The same contact spring couple 5, 6 over which the cut- 80 off relay is connected to the test wire serves namely also to lock the cut-off relay after the line relay LR is de-energized. Further, only one contact spring couple 6, 7 is required to control the circuit of the call meter SM. 85 For the rest, the arrangement is the same as in Figure 1 and the operation is also sub- 90 stantially the same. When the line relay LR is energized the contact spring group 5, 6, 7 is actuated in such a manner that the cut-off relay BR is directly connected to the test wire, whereas the call finder SM is disconnected. 95 As said contact spring group is adapted to be actuated also by the cut-off relay, said group will be held in the actuated position by the relay BR even after the line relay LR has been deenergized. The call metering then takes place in the same manner as above by short-circuiting the relay BR over the test wire, the call meter SM then obtaining a current impulse over the contacts 6, 7.

Figure 3 shows an example of the disposition of the contact springs of the relays LR and BR. The contact spring group 8, 9 and 1, 2, 3, 4 are so disposed that they are actu-

ated only by the relay armatures LA and BA respectively whereas the contact spring group 5, 6, 7 is disposed between said groups so that it may be actuated by both armatures.

5 I claim:

1. In a circuit arrangement for telephone plants a subscriber's line, line and cut-off relays connected to said line, a number of contacts appertaining to said cut-off relay and 10 controlling the circuit extending over the test wire, and means to actuate said contacts by the line relay when the latter relay is energized.
2. In a circuit arrangement for telephone 15 plants, a subscriber's line, line and cut-off relays, connected to said line, a number of contacts, appertaining to said cut-off relay, means to actuate said contacts by the line relay when the latter relay is energized, means 20 to connect the cut-off relay to the test wire over contacts which are actuated by the line relay when it is energized, and means to lock said cut-off relay over the same contacts when it is energized over the test wire.
3. In a circuit arrangement according to 25 claim 2, means to disconnect the call meter from and connect it to the test wire over one and the same break contact actuated both by the line relay and the cut-off relay.

30 In testimony whereof I affix my signature.

KNUT LARSSON.
